UNITED STATES PATENT OFFICE.

JESSE H. TROMANHAUSER, OF TORONTO, ONTARIO, CANADA.

METHOD OF CONSTRUCTING CONCRETE CRIBS.

Application filed November 14, 1924. Serial No. 749,837.

To all whom it may concern:

Be it known that I, JESSE H. TROMANHAUSER, of the city of Toronto, in the county of York, Province of Ontario, Canada, a subject of the King of Great Britain, have invented certain new and useful Improvements in Methods of Constructing Concrete Cribs, of which the following is a specification.

10 This invention relates to a method of and apparatus for constructing and placing concrete cribs for sea walls and the like whereby the cribs may be built up in any convenient location and subsequently towed to 15 their ultimate destination and sunk there.

In my prior United States Patent No. 891,966, I have shown and described a method of constructing and placing such cribs which consisted in providing a pontoon 20 with side walls along its edges, building a crib on said pontoon and within its walls, and subsequently sinking the crib and pontoon together. While this procedure was satisfactory with small cribs, it was not so 25 satisfactory with large cribs owing to the expense involved in building a separate pontoon for each crib and to trouble experienced owing to the tendency of the pontoon bottoms to bulge up in the middle.

30 The object of the present invention is to devise a method and means whereby the pontoons may be re-used and the trouble experienced with the upward bulging of the bottoms overcome.

35 I attain my objects by providing a pontoon with low fixed marginal walls and with higher removable walls spaced inwardly from the outer walls. Inside the inner walls the concrete crib is built up to the required 40 height while the pontoon is afloat. The tops of the low walls remain above the water while the removable wall is being positioned and until the concrete is built up to a considerable height, thereafter submerging. After the crib is completed to a 45 height sufficient to enable it to float without extraneous support, the inner side walls are removed and the pontoon bottom stripped off by placing weights on it at one end, and 50 along the sides if necessary, to sink the end wall below the bottom of the concrete crib.

55 The crib is then easily towed away from the pontoon and is then sunk in the desired location. The dismantled pontoon is then relieved of its weights and the inner walls again secured in position, when the pon-

toon is ready for the building of the next crib.

The invention is illustrated in the accompanying drawings in which

Fig. 1 is a side elevation, partly in section, of a crib constructed in accordance with my invention;

Fig. 2 a plan view of the same;

Fig. 3 a side elevation showing the method of stripping the pontoon bottom from the crib;

Fig. 4 a detail of the corner connections of the inner crib walls;

Fig. 5 a detail of the hoisting straps and shackles and fastening bolts of the inner walls.

Referring particularly to Figs. 1 to 5 of the drawings, 1 is the pontoon bottom, which may be of any suitable construction, 75 but which is preferably double and is provided with transverse cross beams 2 at its under side. Secured to the bottom substantially at its edges are the fixed walls 3. By fixed is to be understood that the walls normally remain in position, though they might, of course, be so constructed that they might be removed if occasion required.

Spaced inwardly from the fixed walls are the detachable walls 4. These walls preferably are of a greater height than the walls 3. While any suitable means might be employed for securing these walls to the bottom and to one another, I prefer to employ the means shown particularly in Figs. 4 and 90

5. A plurality of bolts or wall rods 5 are provided, each having its upper end 6 adapted for engagement by a wrench, while the lower end 7 is threaded. The walls 4 are provided with suitable openings for the passage of these wall rods, which are provided with shoulders 8 adapted to engage the upper sides of the walls. The ends 7 are adapted to screw into nuts 9 bolted securely to the bottom 1. The walls 4 at the corners are provided with clamp members 10 securely bolted thereto and adapted at their outer ends for the passage of the bolts 11.

To each wall 4 are secured a plurality of hoisting straps 12 each having an opening therethrough adjacent its upper end for the passage of the bolt 13 by means of which a hoisting shackle 14 will be secured to the strap.

The pontoon is used in the following manner. The pontoon bottom with its fixed walls in position is securely moored in quiet

waters, and the detachable walls are then secured in position by means of the wall rods 5 and the clamps 10. A hollow crib formed of concrete is then built up within 5 the detachable walls 4 in the manner described in my prior patent hereinbefore referred to, suitable inlet valves 16 being positioned in the bottom of the crib and apertures 17 through any transverse walls 10 which may be formed within the crib. The fixed walls 3 exclude water from the upper surface of the bottom until the detachable walls are secured in position. As the concrete crib is built up, these walls are gradually submerged and the duty of protecting the crib during construction devolves upon the walls 4, which will usually be high enough so that when the concrete crib is built up high enough to make the crib self- 20 floatable, the upper edges of these walls are still near or above the surface of the water.

The pontoon is then stripped from the completed crib in the following manner. The clamps 10 are disconnected and the wall 25 rods 5 withdrawn. The side walls are then stripped from the crib by means of suitable prying tools. Weights are then placed at one end of the pontoon bottom between the end of the crib and the end wall 3, and the 30 end of the pontoon bottom forced down until the upper edge of the end wall is below the bottom of the concrete crib. The whole bottom is then easily towed clear of the crib, which then may be filled with 35 water through the valves 16 and sunk in position, thereafter being filled with solid material.

By using the pontoon constructed as described, and in the manner set forth, each 40 pontoon is available for the construction of a plurality of cribs, a great saving both in time and material being thus effected. The side walls are provided with hoisting straps 12 having shackles 14 connected thereto by 45 means of which the walls may be lifted.

To overcome the tendency of the pontoon bottom bulging upwardly in the middle or "hogging," I provide the bottom of the crib with ballast 21. Preferably this ballast is carried between the double walls of the bottom 1 and is formed of a plurality of concrete slabs arranged longitudinally of the bottom and substantially at right angles to the cross beams 2.

Another object of using this ballast is to 55 reduce the buoyancy of the bottom of the pontoon, so that it will not be necessary to use so many weights on the pontoon bottom when it is desired to remove the bottom from below the crib.

What I claim is:

1. The method of constructing a concrete crib which consists in providing a pontoon bottom with removable side walls; building 5 a floatable crib with concrete walls on said

pontoon bottom within the pontoon walls and while the pontoon is afloat; disconnecting and stripping the pontoon sides; and finally stripping the pontoon bottom from below the crib. 70

2. The method of constructing a concrete crib which consists in providing a pontoon bottom with removable side walls spaced inwardly from the edges of the bottom; building a floatable crib with concrete walls on said pontoon bottom within the pontoon walls and while the pontoon is afloat; disconnecting and stripping the pontoon sides; and finally stripping the pontoon bottom from below the crib by weighting. 75

3. A method of constructing a concrete crib which consists in providing a pontoon bottom with permanent side walls and with removable side walls spaced inwardly from the permanent walls; building a floatable crib with concrete walls on said pontoon bottom within the inner pontoon walls and while the pontoon is afloat; disconnecting and stripping the inner pontoon sides; and finally stripping the pontoon bottom from below the crib. 80

4. The method of constructing and placing a concrete crib which consists in building a hollow crib afloat; supporting it during building by a structure serving both as a float and a form; stripping said structure from the crib; and finally sinking the crib in position. 85

5. A pontoon for the construction of concrete cribs comprising a pontoon bottom; fixed substantially watertight walls secured thereto around its edges; and detachable walls also secured thereto in spaced relationship to the fixed walls and adapted to form outside mold walls. 90

6. A pontoon for the construction of concrete cribs comprising a buoyant pontoon bottom; and detachable walls secured thereto and spaced inwardly from the edges of said bottom and adapted to form outside mold walls. 100

7. A buoyant pontoon comprising a pontoon bottom; four detachable walls spaced inwardly from the edges of said bottom; bolts extending from top to bottom to form outside mold walls of said walls detachably securing the walls to the pontoon bottom; and clamps releasably securing the ends of the walls together. 115

8. A pontoon for the construction of concrete cribs comprising a buoyant pontoon bottom; detachable walls secured thereto and spaced inwardly from the edges of said bottom to form outside mold walls; and ballast for the pontoon bottom positioned to resist the hogging of the bottom when the load is applied adjacent the edges. 125

9. A pontoon for the construction of concrete cribs comprising a double pontoon bottom; detachable walls secured thereto 130

and spaced inwardly from the edges of said bottom to form outside mold walls; and ballast for the pontoon positioned within the double bottom to resist the hogging of the bottom when the load is applied adjacent the edges.

10. A pontoon for the construction of concrete cribs comprising a buoyant pontoon bottom; detachable walls secured thereto and spaced inwardly from the edges of said bottom to form outside mold walls; and hoisting straps secured to said walls.

11. A pontoon for the construction of concrete cribs comprising a pontoon bottom; fixed substantially watertight walls secured thereto around its edges; and detachable substantially watertight walls also secured thereto in spaced relationship to the fixed walls, said detachable walls being of greater height than the fixed walls and adapted to form outside mold walls and to act as pontoon walls when the lower fixed walls have become submerged.

12. A pontoon for the construction of concrete cribs comprising a pontoon bottom; fixed substantially watertight walls secured thereto around its edges; and detachable substantially watertight walls also secured thereto in spaced relationship to the fixed walls, said detachable walls being of greater height than the fixed walls and adapted to form outside mold walls and to act as pontoon walls when the lower fixed walls have become submerged; and hoisting straps secured to said detachable walls.

13. A pontoon for the construction of concrete cribs comprising a pontoon bottom; fixed substantially watertight walls secured thereto around its edges; and detachable substantially watertight walls also secured thereto in spaced relationship to the fixed walls; bolts extending from top to bottom of said detachable walls securing the walls to the pontoon bottom; and clamps releasably securing the ends of the walls together, said detachable walls being of greater height than the fixed walls and adapted to form outside mold walls and to act as pontoon walls when the lower fixed walls have become submerged.

14. A pontoon for the construction of concrete cribs comprising a buoyant double pontoon bottom; fixed substantially watertight walls secured thereto around its edges; and detachable substantially watertight walls also secured thereto in spaced relationship to the fixed walls, said detachable walls being of greater height than the fixed walls and adapted to form outside mold walls and to act as pontoon walls when the lower fixed walls have become submerged; and ballast for the pontoon positioned within the double bottom to reduce the buoyancy of the pontoon and resist the hogging of the bottom when the load is applied adjacent the edges.

Signed at Toronto, Canada, this 16th day of October 1924.

JESSE H. TROMANHAUSER.
